UNITED STATES PATENT OFFICE

MAX AURIG AND GEORG BRÜCKLMAYR, OF MUNICH, GERMANY, ASSIGNEES TO LUISE THEISEN AND FRED HANS THEISEN, BOTH OF MUNICH, GERMANY

APPARATUS FOR CENTRIFUGALLY TREATING GASES, VAPORS, AND THE LIKE

Application filed June 24, 1929, Serial No. 373,396, and in Germany July 6, 1928.

Our invention relates to improvements in centrifugal apparatus for cleaning, cooling, mixing or otherwise treating gases, vapors, liquids and the like. The invention concerns 5 apparatus of the type in which the substance to be treated is subjected to the centrifugal action of a rotor comprising discs mounted for rotation in a casing or housing.

The principal object of our invention is to 10 increase the efficiency of this type of apparatus and we accomplish this object, primarily, by the use of discs with surface projections or irregularities, as distinguished from the use of plane discs or plates as here- 15 tofore. By employing discs with surface projections or irregularities, the friction against the discs of the substance being treated is increased, the centrifugal action of the discs is enhanced and greater pressure and 20 consequently increased advance of the gas and/or liquid through the apparatus are achieved.

The invention is illustrated in the accompanying drawings, in which Fig. 1 is a trans- 25 verse section of a fragment of the complete apparatus; Fig. 2 is an elevation of a fragment of a disc having radial projections; Fig. 3 is a similar view of a disc fragment in which the projections are radially inclined; Fig. 4 is an edge view of a plurality of discs 30 in which the projections are formed by nuts and bolts; Fig. 5 is an elevation of a fragment of the disc of Fig. 4; Fig. 6 is an edge view of a plurality of discs in which the pro- 35 jections are carried by the spacers between adjacent discs; Fig. 7 is an elevation of a fragment of a disc having winged projections. Fig. 8 is a view somewhat like Fig. 1, 40 but in which the projections of the discs ex- 45 tend alternately at opposite faces of the disc; Fig. 9 is an elevation of a fragment of a disc of Fig. 8 with the projections forwardly in- 50 clined; Fig. 10 is a similar view with the pro- 55 jections rearwardly inclined; Fig. 11 is a sim- 60 ilar view with the projections radial; Fig. 12 is a fragmentary elevation of a modi- 65 fication in which a wheel is used in lieu of a disc with the projections in the spokes or arms of the wheel; Fig. 13 is an edge view of 70 a series of discs like those of Fig. 12; Fig. 14

is a fragmentary elevation of a modified form 55 of wheel in which the spokes or arms are curved instead of being radial; Fig. 15 is a fragmentary cross section and Fig. 16 a fragmentary elevation of a structure in which a series of flat rings with projections is used instead of discs.

In all the forms shown in the drawings it 60 will be observed that the discs are provided with some form of projections, and while the projections differ from one another in form and in some cases in the direction in which they extend, the purpose of all forms is to increase the efficiency of the apparatus as a 65 whole.

Referring to Fig. 1 of the drawings, 10 de- 70 notes the housing or casing wherein rotates a plate 11 which carries the discs denoted generally as 12. The plate 11 is mounted on a rotary shaft 13 which, when it rotates, carries the plate and discs around with it. Secured approximately centrally to the plate 11 is a perforated distributing cone 14 to 75 which the substance to be treated is supplied usually under pressure, through the supply pipe or nozzle 15. The parts so far described are old and well known in the art and require no detailed description.

In the operation of a device of this character, the substance or mixture to be treated, say gas and washing liquid, is introduced 80 through the pipe 15 into the distributing cone 14 whence it passes to the discs 12 which, by centrifugal action, bring about the desired result, whether it be a mixing effect, a scrub- 85bing or purifying of gases, the cooling thereof, etc.

The discs 12 are secured to the plate 11 by 90 rods or bars 16 and are held suitable dis- 95 tances apart thereon by the interposed spacers 17.

In Fig. 2, the disc 12^a has struck up radial 95 projections 18 and in Fig. 3, the disc 12^b has struck up radially inclined projections 18^a.

In Figs. 4 and 5 the discs 12^c have projec- 95 tions in the form of nuts and bolts 18^b of any desired shape and preferably arranged so that the projections in one disc are staggered with relation to the projections of an adja- 100 cent disc.

The form of Figs. 6 and 7 differs slightly from the preceding forms in that the discs 12^d do not directly carry projections, but such projections 18^e which are preferably wing or blade shaped, are carried by or formed on the spacer members 17^a. The projections 18^e, although not carried directly on or by the discs, are closely adjacent thereto and in effect form part thereof.

10 Figs. 8 to 11 disclose a construction in which the projections are struck up from the disc 12^e and alternate projections extend from opposite faces of the disc. In Fig. 8, 10^a is the casing, 11^a the disc supporting plate 15 and 13^a the shaft upon which the plate is mounted. Each disc 12^e has struck up therefrom projections 18^d and 18^e, the former extending to the left of the disc and the latter to the right thereof. It will be noted that 20 the projections on one side of one disc extend into the spaces between the projections on the opposed face of the adjacent disc. In Fig. 9 the projections 18^d and 18^e are inclined forwardly or in the direction of rotation of the 25 disc, in Fig. 10 the projections are inclined rearwardly or opposite the direction of rotation of the disc and in Fig. 11 the projections are radial.

In Figs. 12 to 14 wheels in lieu of discs are 30 shown. The wheel 12^f of Fig. 12 has radial arms or spokes 19 from which are struck up projections 18^f and 18^g extending alternately at opposite faces of the disc as shown in Fig. 13 and, also as shown in that figure, with the 35 projections at one face of one disc extending into the spaces between the projections on the opposed face of the opposite disc. Except for the use of a wheel instead of a disc, the construction is similar to that of Figs. 8 to 40 11. In Fig. 14 the arms 19^a of the wheel 12^f are curved, but in other respects the construction is analogous to that of Figs. 12 and 13.

In Figs. 15 and 16 the rings 12^h with projections 18^h are shown, these rings being used 45 in some cases in lieu of the discs or wheels shown in certain of the other views of the drawings.

We claim:—

1. In a centrifugal apparatus for the purpose specified, the combination with a casing, of a rotor therein comprising discs spaced apart and having each a plurality of series of surface projections each series of projections extending in a line from the hub to the periphery of the disc and constituting a rib with numerous interruptions, the projections on the face of one disc extending into the spaces between the projections on the opposite face of an adjacent disc, and a horizontal shaft 55 supporting and adapted to rotate all the discs within the casing.

2. In a centrifugal apparatus for the purpose specified, the combination with a casing, of a rotor therein comprising discs spaced apart, a plurality of series of nuts and bolts

projecting from the faces of the discs and each such series extending in a line from the hub to the periphery of a disc and constituting a rib with numerous interruptions, and horizontal shaft supporting and adapted to rotate all the discs within the casing.

3. In a centrifugal apparatus for the purpose specified, the combination with the elements claimed in claim 2, of spacing members fixed to the discs between the same and carrying said projections.

4. In a centrifugal apparatus for the purpose specified, the combination with a casing, of a rotor therein comprising rotatable discs only said discs spaced apart and having each a plurality of series of surface projections each series of projections extending in a line from the hub to the periphery of the disc and constituting a rib with numerous projections, a horizontal rotatable shaft extending into said casing and means securing each disc in the casing to said shaft whereby rotation of said shaft effects rotation of each and every disc in the casing.

In testimony whereof we affix our signatures.

MAX AURIG.
GEORG BRÜCKLMAYR.
